UNITED STATES PATENT OFFICE.

PAUL SCHMIDT, OF GARWOOD, NEW JERSEY.

SLIDING LATCH.

Application filed August 30, 1924. Serial No. 785,986.

This invention relates to locks and latches and more particularly to a novel and improved key operated, sliding latch which may be opened and closed from either side of a door or closure.

One of the objects of my invention is to provide a key operated lock or latch including a series of meshed gears and rack bars which are limited in their movement 10 in their open and closed positions.

A further object of my invention is to provide a lock or latch of the character above specified, wherein a pair of relatively movable rack bars are operable by a key 15 actuated series of meshed gears.

A further object of my invention is to provide a lock or latch which is extremely simple in construction, highly efficient in operation and use, easily assembled, practical, durable, capable of a multiplicity of uses and otherwise cheap to manufacture.

In the drawings, forming a part of this specification,

Figure 1 is a view showing the latch bars 25 and meshed gears in position on the inner side of the door or closure.

Figure 1^a is a sectional view taken on the line 1^a—1^a of Figure 1.

Figures 2 and 3 are views of different 30 type of keys.

Figures 4 and 5 are end views of gears having different types of gear teeth.

Figure 6 is a view showing the open position of the latch bars on the door.

Referring now to the drawings, wherein like reference characters designate corresponding parts throughout the several views, 35 5 designates the inside of a door or closure and 6 the door jamb. The lock or latch 40 proper consists of a horizontal, rack bar 7, which cooperates with a vertical rack bar 8, constructed and arranged to operate so that the rack bar 7 will be limited in its movement by the bar 8, when the latter has 45 reached its maximum, vertical position, when in engagement with a stop 9, permanently secured to the door. The inner end of the bar 7 and the lower end of the bar 8 is cut away at an angle of substantially 45 degrees so that when the said ends of the bars 50 are in engagement, they form a right angle. Both of the bars are slotted as at 10, 11, 55 and are slideable on a pair of lugs 12, 13, permanently attached to the inner face of the door or closure. The opposite end of the rack bar 7 is somewhat enlarged as in-

dicated at 14, and adapted to engage an abutment or stop 15 on the door jamb.

The teeth 16, 17, of the respective rack bars 7, 8, mesh with a pair of gears 18, 19, 60 each mounted on a shaft 20, 21. The said gears mesh with a pair of pinions 22, 23, offset with respect to each other, the said pinions being also mounted on short shafts. 65 The pinions meshing with the gears and the said gears meshing with the rack bars, as the pinions are rotated in a clockwise direction, the rack bars will separate as clearly shown in Figure 6. In order to affect this operation, I provide a specially constructed 70 key 25 having a cylindrical toothed portion 26 formed on the shank 27, which key is adapted to mesh with the teeth of the pinions when the said key is inserted through an opening in the door, for instance. It will 75 thus be seen that upon the rotation of said key to the left or to the right will lock or unlock the door as above shown.

In Figure 8, a similar type key is shown 80 wherein the toothed portion 28 may be varied to conform to the teeth 29 of a pinion or to the teeth 30 of a different shaped pinion to be substituted for the pinions 22, 23. In each instance, however, the respective teeth of the pinions and the key must 85 properly engage in order to affect the operation desired.

It will be seen that as the latch bar 7 moves to the right, and to its open position, the cooperating rack bar 8 moves upwardly 90 at the same time. As the bars separate, the ends 31 of the bar 7 moves inwardly being limited however, in such movement when the upper end 32 of the rack bar 8 abuts the stop 9.

It is of course understood that in the type of latch shown, the door or closure swings in one direction, that is, outwardly, so that the rack bar 7 must be withdrawn from the position shown by Figure 1 to the position shown by Figure 6 before the door may be opened. The door, of course, may be latched either from the inside or the outside, since by the rotation of the key in operating the gears and the respective rack bars, will 105 move the latter to the locked and unlocked positions.

While I have illustrated and described my invention with some degree of particularity, I realize that in practice various alterations therein may be made. I therefore reserve the right and privilege of changing the 110

form of the details of construction or otherwise altering the arrangement of the correlated parts without departing from the spirit of the invention or the scope of the 5 appended claims.

Having thus shown and described my invention, what I claim as new and desire to secure by United States Letters Patent is:—

1. A lock of the class described comprising 10 a rack bar, a second rack bar movable at right angles relatively to the first mentioned rack bar, one end of each of the said bars engaging each other in one position, guides for said bars, gears engaging each 15 of the rack bars, pinions meshing with the gears and a gear toothed key adapted to mesh with the aforesaid pinions for the purpose of actuating the said pinions and gears for moving the respective rack bars 20 to their open and closed positions.

2. A lock of the class described, comprising 25 a bolt having teeth thereon in meshed engagement with a gear member and a pinion in mesh with the said gear member, a stop bar also provided with teeth in mesh 30 with an adjacent gear member which is in turn meshed with a pinion, the two said pinions set at a distance from each other and in position to engage a gear toothed key when inserted between them and to be

rotated thereby to actuate the aforesaid bolt and stop bar in specific relation to each other, substantially as shown and described.

3. A lock of the class described, comprising 35 a bolt toothed on one of its sides and engaging a gear member which is in turn in mesh with an adjacent pinion, a stop bar toothed on one of its sides and engaging a gear having a pinion in mesh therewith, the teeth of the said gears and pinions cut and spaced in distinctive formation and adapted 40 to engage and to be operated by a gear cut key coinciding with the aforesaid distinctive teeth, substantially as shown and described.

4. A lock of the class described, comprising 45 a slidable bolt, a slidable stop bar adjacent to the said bolt at its rear extremity, toothed edges on the said bolt and stop bar and gear wheels in mesh therewith and pinions in mesh with the said gear wheels and the said pinions so placed as to be apart 50 from each other, but capable of operation together by means of an inserted key, gear cut to mesh therewith, substantially as shown and described.

Signed at Garwood, in the county of Union and State of New Jersey, this 14th day of July A. D. 1924.

PAUL SCHMIDT.
